UNITED STATES PATENT OFFICE.

HARRY KLITZNER, OF PROVIDENCE, RHODE ISLAND.

DESIGN FOR A RING.

Application filed September 6, 1921. Serial No. 498,911. Term of patent 3½ years.

To all whom it may concern:

Be it known that I, HARRY KLITZNER, a citizen of the United States, residing at the city of Providence, county of Providence, and State of Rhode Island, have invented a new, original, and ornamental Design for a Ring, reference being had to the accompanying drawing, forming a part thereof.

The figure is a perspective view of a ring, illustrating my new design.

I claim:

The ornamental design for a ring, as shown.

HARRY KLITZNER.
